UNITED STATES PATENT OFFICE.

NICHOLAS RIPPENBEIN, OF PERTH AMBOY, NEW JERSEY.

DISPLAY CONTAINER.

Application filed June 5, 1923. Serial No. 643,523.

To all whom it may concern:

Be it known that I, NICHOLAS RIPPENBEIN, a citizen of the United States, and resident of Perth Amboy, in the county of Middlesex and State of New Jersey, have invented certain new and useful Improvements in Display Containers, of which the following is a specification.

My invention relates to an improved display container wherein goods may be packed for storage and shipping and when received by a customer the container may be set up in such a manner as to expose the goods, and whereby the goods may be described upon suitable display or advertising located upon display panels of the container.

In many kinds of containers for goods heretofore made it has been possible to pilfer the goods without interference from parts of the container, and one of the objects of my invention is to provide a container which will display the goods therein and at the same time will secure a pronounced degree of security to the goods in the container, to deter pilfering the same, without materially sacrificing the time or effort of the retailer in extracting individual packages of articles from the container for sale.

Other objects of my invention are to afford a vertical view of the faces of the packages or goods within the container so that portions thereof may be clearly seen; to provide a compact grouping so that a minimum amount of frontage and depth of package is demanded upon the retailers' show case or counter; to afford an arrangement for securely retaining the principal advertising panel of the container in a definitely erected position, and to provide an exceptionally attractive ensemble.

My invention also comprises novel details of improvement that will be more fully hereinafter set forth and then pointed out in the claims.

Reference is to be had to the accompanying drawings forming a part hereof, wherein,

Fig. 1 is a perspective view showing my improved display container in a closed position to contain goods;

Fig. 2 is a cross section on line 2, 2, in Fig. 1;

Fig. 3 is a front view of the container showing the parts opened for display;

Fig. 4 is a cross section on line 4, 4, in Fig. 3;

Fig. 5 is a perspective view showing the display panel open, looking from the side opposite that shown in Fig. 1;

Fig. 6 is a perspective view illustrating a modification and showing the container partly closed;

Fig. 7 is a face view illustrating the container shown in Fig. 1, embodying a modification of the panel that closes the front opening of the container;

Fig. 8 is a face view of a blank for the container of Figs. 1 to 5;

Fig. 9 is a detail of the removable safety flap for the front opening of the container;

Fig. 10 is a detail of a modified safety flap for the front opening of the container;

Fig. 11 is a face view of a blank for the container of Fig. 6;

Fig. 12 is a perspective view illustrating my improved display container in position upon an easel-like cover;

Fig. 13 is a perspective view of the easel-like cover, and

Fig. 14 is a perspective view illustrating the easel-like cover and display container assembled for shipping and storage.

Similar numerals of reference indicate corresponding parts in the several views:

My improved display container is shown in substantially box-like form having a front or primary wall 1, side or intermediate walls 2, 3 and a back or secondary wall 4. In the form shown in Figs. 1 to 6 and Fig. 8 the side walls are joined to the front wall 3 by means of the score lines 5, 6, of the blank, (Fig. 8), and the back wall 4 is joined to the wall 2 by the score line 7. When the blank is folded along said score lines into rectangular shape the tab 8 at the outer side of the wall 4 may be secured to the wall 3 by means of adhesive, indicated at 9. The front wall 1 is provided with an opening 10 through which the goods or packages 11 may be displayed. Said goods may be put up in any suitable way. In the accompanying drawings I have illustrated packages at 11, the display container being of any suitable dimension to contain any desired number of packages, portions of which will appear through opening 10. The bottom of the box may be closed by any suitable means. I have shown the sides 2, 3, provided with flaps 2^a, 3^a, to be folded

inwardly and the back wall 4 provided with a flap 4^a to be folded upon the flaps 2^a, 3^a, said flaps being foldable along the score lines 2^b, 3^b, and 4^b, respectively, as illustrated in the blank in Fig. 8. The corresponding lower edge of front wall 1 is provided with a tongue 12 hinged to said wall by the score line 12^a of the blank adapted to fold over the flap 4^a, said tongue 12 being shown provided at its sides with lips 12^b adapted to enter the slits 4^c in the flap 4^a to retain the parts 2^a, 3^a, 4^a and 12 closed at the adjacent end of the container; in a well known manner. The upper portion of the wall is provided with an upper extension in the form of a display panel, indicated at 14, which is adapted to fold over the open end of the container along the score line 15, as shown in the blank in Fig. 8, whereby the panel is hinged to said wall. The portions 14^a are lateral extensions of the panel and also upward extensions of the walls 2 and 3 and are hinged to the panel at score lines 15^b and to walls 2 and 3 by score lines 15^c. Said portions are scored diagonally at 15^a so that they may be folded diagonally. The back wall 4 is provided with a tongue 16 shown having end lips 16^a. The opening 10 is provided with a safety panel 17 which is cut from the blank along the lines 17^a and hinged to the front wall along the score line 15, whereby said safety panel may be swung within the container over the packages or goods therein, as indicated in Figs. 2, 4 and 5 when the container is to be closed. The blank may be cut through at 17^b so that the safety panel will hinge along the score line at 17^c.

A detachable protective insert for the opening 10 in the front wall of the container is indicated at 18. Said insert comprises a main panel substantially corresponding to the opening 10, said main panel having marginal sections at 18^a adapted to be inserted behind the edges at the bottom and sides of opening 10. To permit ready bending of the protective insert 18 to insert its marginal sections 18^a in position behind the edges of front wall 1 at opening 10 said insert may be provided with diagonal score lines at 18^b, as indicated in Figs. 1, 9 and 10. When the insert is located within opening 10, of front wall 1, the packages or goods within the container will be protected for storing and shipping.

When the container is assembled and the packages have been placed therein the safety panel 17 may be folded upon the packages and the protective insert 18 will be placed within opening 10 and an upper section 18^c of said insert that is foldable along the transverse score line 18^a, will be folded together with panel 14 and the portions 14^a inwardly over the open end of the container, (see Figs. 1 and 2), said portions

14^a folding in a triangular manner along the score lines 15^a and the flap 16 will be folded upon the panel 14, the lips 16^a of said flaps being tucked under the adjacent angular edges of the portions 14^a, as indicated in Fig. 1.

When the display container is to be used the flap 16 will be raised, the insert 18 will be removed, the panel 14 will be extended upwardly with its side portions 14^a flaring laterally, and the flap 16 will be laid over the packages, either upon or under the safety panel 17 to overlie the goods or packages, (Fig. 5). Any desired advertising or display may be produced upon the panel 14 and its angle portions 14^a so that when the container is opened an attractive appearance will be afforded, and at the same time the goods will be exposed through the front opening 10 of the container. Since the flap 16 and panel 17 are upon the packages of goods behind the panel 14 they will render a considerable degree of security against pilfering the goods in the container, since it would be necessary for a pilferer to raise the flap 16 and the panel 17 in order to obtain access to the goods or packages within the container which would entail considerable time and be a deterrent against pilfering lest the pilferer be detected.

In Fig. 10 the section 18^c of the insert 18 is of sufficient extent to extend across the top of the container and is provided with a score line at 18^d affording a tuck at 18^e that may be folded along said score line and tucked between the packages in the container and the back wall 4 thereof. With this construction, the tongue 16 may be dispensed with and the back wall 4 need have no upward extension.

The relation of the main walls of the container and the manner of securing them together in rectangular form, as before described, may be altered. In the form of container shown in Fig. 6, and in accordance with the blank shown in Fig. 11, the back wall 4 is connected to the lower front edge of front wall 1 by means of a bottom wall 19, the blank having score lines at 20, 21 uniting said wall to the front wall 1 and back wall 4 respectively and the sides of back wall 4 are provided along score lines 5^a and 6^a with extending sections or wings 4^d upon which adhesive may be applied at 22 to secure the sections 4^d to the side walls 115 2, 3. The sides 2 and 3 are shown provided with median score lines 23, 24, which extend through the angle sections 14^a, and the bottom section 19 is provided with median score line 25 between the score lines 20, 21, as indicated in the blank of Fig. 11. When the parts of the container are assembled in rectangular form, as stated, the container may be collapsed for shipping or storage by folding the bottom section 19 inwardly along 125 130

line 25 and folding the sides 2, 3, outwardly along in the lines 23, 24, in the manner indicated in Fig. 6, whereby the container may be delivered in a small compass for 5 shipping and may be readily opened out for use. Score lines 23, 24, 25 serve in a manner corresponding to similar score lines set forth in my application filed December 3, 1922, Serial No. 609,805 for merchandise 10 container.

Instead of providing the safety panel 17 mainly cut out along the line 17^a of the front wall, the cuts may be provided at 17^a and uncut portions left at 17', (Fig. 7), so 15 that the panel 17 will serve as a protection for the contained goods or packages for storage and shipping, and said panel may be detached at the parts 17' when the goods are to be displayed, said panel in such case 20 serving in the nature of the protective insert 18.

The opening 10 in the front wall may be covered with a piece of transparent material, such as gelatine, which can be attached 25 to parts of said wall adjacent to the opening by means of adhesive, in a conventional and well known manner. The front wall may have any desired number of openings, such as 10.

30 Panel 14 or portions 14^a or both may be held down in place when the container is in a closed position by providing any of them with lips for gluing on to the back wall, or by providing any of them with a 35 tuck for inserting downward, between the back wall and the container's contents or a tongue extension for inserting into slits in the back wall, or by any equivalent means.

40 The form of insert shown in Fig. 10 may be used by placing the main part 18 upon closed panel 14, folding the sections 14^a thereon, folding part 18^c at score line 18^a, over said sections and inserting the tuck 18^f 45 inward along the back wall 4, in manner before described.

50 My improved container may be enclosed in any suitable wrapping or box for shipment and storage. In the form shown in Figs. 12, 13 and 14 my improved display container is adapted to be enclosed within a cover or box having a box-like section at 26 provided with a section 27 adapted to receive my improved container, as indicated 55 in Fig. 14. When the goods are to be displayed the container is removed from the sections 26, 27, the latter may be set up with section 27 in front of the section 26, and my improved display container placed upon 60 the section 27 and retained in display position resting against section 26. The sections 26, 27 are similar to corresponding parts shown in my application for display containers filed January 19, 1923, Serial No. 65 613,578.

Having now described my invention what I claim is:

1. A display container having an opening for the admission and extraction of contents, said container having an additional 70 opening in one of its walls for display of the contents of the container, said container having a detachable protective insert for the second named opening, said insert comprising a main portion substantially corresponding to said opening and having marginal sections extending from said main portion, said marginal sections being adapted to slide under and lie in contact with the parts of said wall adjacent to the second named 75 opening, said protective insert having a portion adapted to extend over the first named opening.

2. A display container having a back wall, a pair of side walls, and a front wall 85 corresponding to and suitably spaced from said back wall, said front wall having an opening and an upper extension, said extension constituting a display panel, said display panel having portions attached 90 to said side walls at the ends of said panel constituting angle sections located substantially between the planes of the aforesaid front and back walls, in which the display panel is hinged to the 95 top edge of the front wall to bend backwardly therefrom to a position in angular relation to said front and back walls, the end portions of said panel being provided with oblique score lines directed toward the top edge of said front wall, said score lines serving to permit the end portions of the panel to collapse when said panel is bent 100 backwardly, said front wall having a safety panel, said safety panel comprising material of the front wall left from making said opening, said safety panel being hinged to the upper portion of said wall and adapted to extend rearwardly from said wall to 105 overlie the contents of the container. 110

3. A display container as set forth in claim 2 having a detachable protective insert for said opening, said insert comprising a main portion substantially corresponding to said opening and having marginal sections extending from the main portion, said marginal sections adapted to slide under the parts of the front wall adjacent to said opening. 115

4. A display container having a back wall, 120 a pair of side walls, and a front wall corresponding to and suitably spaced from said back wall, said front wall having an opening and an upper extension, said extension constituting a display panel, said display panel having portions attached to said side walls at the ends of said panel constituting angle sections located substantially between the planes of the aforesaid front and back walls, in which the display panel is hinged 125 130

to the top edge of the front wall to bend backwardly therefrom to a position in angular relation to said front and back walls, the end portions of said panel being provided with oblique score lines directed toward the top edge of said front wall, said score lines serving to permit the end portions of the panel to collapse when said panel is bent backwardly, said back wall having an upper flap provided with interlocking means engageable with said end portions of the panel when the latter are in collapsed position.

5. A display container as set forth in claim 4 having a detachable protective insert for said opening, said insert comprising a main portion substantially corresponding to said opening and having marginal sections extending from the main portion, 10 said marginal sections being adapted to slide under the parts of the front wall adjacent to said opening.

6. A display container having a bottom, a series of upright walls, and an open top, 15 one of said upright walls having an opening, a display panel hinged to said wall's upper edge and a safety panel comprising material of said wall left in cutting said opening, said safety panel being of such 20 dimensions as to extend angularly from said

wall and oppose the contents of said container at said open top.

7. A display container having a primary wall, a secondary wall corresponding thereto, and a pair of intermediate walls joining said primary and secondary walls together, said primary wall having a panel hinged to a main edge thereof, said panel having side edges angular to said main edge, said intermediate walls and panel 25 having angle sections hinged thereto, said angle sections having score lines oblique to said side edges to permit said panel and angle sections to fold into a closed position over the container with said panel in angular relation to said primary and secondary walls and with said angle sections opposing said panel, said secondary wall having means for interlocking with said panel and angle sections when the latter are in said 40 closed position.

8. A display container as set forth in claim 7 in which the interlocking means comprise a flap hinged to said secondary wall, said flap having wing extensions, said flap being adapted to rest over said panel and angle sections and each of said wing 45 extensions adapted to rest between said panel and an adjacent angle section.

NICHOLAS RIPPENBEIN.
